UNITED STATES PATENT OFFICE.

CHARLES F. LEFEVER, OF PLYMOUTH, MICHIGAN, ASSIGNOR TO DAISY MANUFACTURING CO., OF PLYMOUTH, MICHIGAN, A CORPORATION OF MICHIGAN.

AIR-GUN.

1,390,569.

Specification of Letters Patent. Patented Sept. 13, 1921.

Application filed December 20, 1920. Serial No. 431,815.

To all whom it may concern:

Be it known that I, CHARLES F. LEFEVER, a citizen of the United States of America, residing at Plymouth, in the county of Wayne 5 and State of Michigan, have invented certain new and useful Improvements in Air-Guns, of which the following is a specification, reference being had therein to the accompanying drawings.

10 The invention relates to air guns and has for its object the obtaining of a construction of breech loader which simulates the action of a breech-loading fire arm. It is also an object to obtain perfect safety in operation, 15 avoiding the possibility of catching the fingers in the breech in case of premature release of the spring. With these objects in view the invention consists in the construction as hereinafter set forth.

20 In the drawings:

Figure 1 is a longitudinal section through a gun showing in full lines the loaded position and in dotted lines the position after firing;

25 Fig. 2 is a similar view showing the position when ready for loading;

Figs. 3 and 4 are cross-sections on line 3—3 and 4—4 of Fig. 1.

A is the false barrel, B the stock, and C 30 the frame connecting said stock and false barrel. D is an abutment located at the rear of the false barrel, and E is the true barrel which extends from said abutment forward. Within the frame C is arranged a barrel F the forward end of which is in contact with the abutment D, while said barrel at its rear end is pivotally mounted on the pin G. H is an air compression cylinder 35 slidably mounted within the barrel F. I is the plunger or piston within the air cylinder, and I' is the plunger shank extending rearward therefrom. J is a spring abutment secured within the barrel F near the rear end thereof, and K is the spring, one end of 40 which bears against said abutment while the other end is in engagement with the piston I. The abutment J is hollow and is apertured at its forward end for the passage of the plunger shank I', the rear end of which has 45 a groove I² therein for engagement with the sear L, which latter is pivotally secured at 50 L' between flanges J' of the member J. The

sear has a rearwardly extending arm L², which is in operative relation to the trigger M pivotally mounted on the pin M'.

55 The construction as thus far described is one in which the spring is placed under compression by sliding the cylinder H together with the piston I and shank I' rearward until the sear L engages the groove I² in said shank. This movement is effected by a lever actuating mechanism, which first draws the cylinder rearward as described and then returns it to its initial position. It is, however, necessary to provide means for loading 60 the barrel E, which is accomplished by cutting away the top of the frame and by moving the barrel F downward so as to expose the abutment D and entrance end of the barrel E. Such movement is accomplished simultaneously with the compression of the 65 spring by the following construction:

70 At the forward end of the cylinder H is the air discharge tube N which telescopes into the barrel E and forms a means for 75 forcing the shot to its seat. This air tube therefore forms a guide for holding the cylinder H in alignment with the false barrel until in its rearward movement the tube 70 N is disengaged from the barrel E. As soon 80 as thus disengaged, the barrel F being pivoted on the pin G is free to be depressed, exposing the breech of the shooting barrel. The actuating mechanism for accomplishing this movement comprises the lever O pivotally attached at P to a downwardly-projecting portion of the frame and coupled by a link Q with a downward projection R on the cylinder H. This downward projection extends through a longitudinal slot in the 85 lower portion of the barrel F and the arrangement is such that when the lever O is operated, it will draw the cylinder H rearward in alignment with the shooting barrel until the tube N is disengaged and will then 90 continue the rearward movement of the cylinder, while the barrel F is depressed by the downward pull of the link Q. During this 95 movement the spring K is being compressed, but as soon as the sear engages with the shank I', the tension of the spring is released so that the barrel F will remain in its depressed position, permitting of loading. 100 When the lever O is swung back to its origi-

nal position, the initial pressure of the links Q will force the barrel F upward to close the breech, while the forward movement of the lever will force the cylinder H forward, 5 engaging the tube N with the barrel E and forcing the shot to its seat. The gun is then ready for firing and the pulling of the trigger will disengage the sear from the shank I', permitting the spring K to force the 10 plunger I forward, compressing the air in the cylinder and discharging the shot.

One of the novel features of the construction is the depression of the barrel F to expose the breech and to simulate the action of 15 a breech-loading fire arm. This action is accomplished with perfect safety regardless of the fact that the spring is being compressed, for any accidental release of the spring will only result in pushing the barrel 20 outward again. In other words, there is nothing which could possibly catch the fingers of the operator in the breech in case of accidental release of the springs. The construction is also simple and inexpensive to 25 manufacture and is one in which the compression of the spring and engagement of the shank with the sear is easily performed.

What I claim as my invention is:

1. In an air gun, the combination with a 30 shooting barrel and a frame rigid therewith, of an air compression cylinder in alinement therewith, a piston in said cylinder, a spring, and means pivoted to said frame for simultaneously compressing said spring and moving said cylinder laterally to expose the breech of the shooting barrel for loading.

2. In an air gun, the combination with a 40 shooting barrel and a frame rigid therewith, of an air compression cylinder normally alined therewith and covering the breech thereof, a piston, a spring, and a lever mechanism upon said frame for simultaneously retracting said piston, compressing said spring and moving said cylinder laterally to expose the breech of said shooting 45 barrel for loading.

3. In an air gun, the combination with a 50 shooting barrel, of a hollow frame cut away adjacent to said shooting barrel, an air compression cylinder within said hollow frame normally in alinement with said shooting barrel, a piston in said cylinder, a piston shank, a spring, a sear, means upon said frame for retracting said piston to compress said spring and engage said shank with said sear and for moving said cylinder laterally to expose the breech of said shooting barrel for loading.

4. In an air gun, the combination with a 60 shooting barrel, of a hollow frame having a portion cut away adjacent to said shooting barrel, a barrel within said hollow frame normally in alinement with said shooting barrel and pivotally mounted at its rear end to permit of downward movement to expose

the breech of said shooting barrel, a cylinder within said pivoted barrel, a piston in said cylinder, a piston shank, a sear mounted within said frame, and a lever mechanism for sliding said cylinder, piston and shank rearward within said pivoted barrel to engage the shank with the sear, said movement also imparting to said pivoted barrel a downward movement which will expose the breech of the shooting barrel for loading. 75

5. In an air gun, the combination with a false barrel, of a shooting barrel therein, a hollow frame secured to said false barrel and cut away adjacent to said shooting barrel to expose the breech thereof, a barrel within said hollow frame normally covering the breech of said shooting barrel and pivotally mounted at its rear end to permit of depression to expose said breech, a cylinder within said pivoted barrel, an air discharge 85 tube for said cylinder telescopically engaging said shooting barrel and holding said pivoted barrel in alinement therewith, a piston within said cylinder, a piston shank, a spring, a sear, a lever for compressing the 90 spring, and a link for connecting said lever with said cylinder, whereby the operation of said lever will retract said cylinder, piston and shank to engage the latter with the sear and will depress said pivoted barrel to 95 expose the breech of the shooting barrel upon the disengagement of said air tube from said shooting barrel.

6. In an air gun, the combination with a false barrel, a frame secured thereto and cut 100 away adjacent to said false barrel, a shooting barrel within said false barrel, an abutment in said false barrel through which said shooting barrel extends, a barrel within said frame pivotally mounted at its rear end to 105 permit of movement into and out of alinement with said false barrel, a cylinder slidably mounted in said pivoted barrel having a downward projection extending through a longitudinal slot in said pivoted barrel, a 110 piston in said cylinder, a piston shank, a spring abutment in the rear of said pivoted barrel, a spring engaging said abutment and piston, a sear mounted in said spring abutment engageable with the end of said piston 115 shank, a trigger for disengaging said sear from said shank, a lever for compressing said spring, and a link connecting said lever with the downward projection upon said cylinder, whereby the movement of said lever 120 will simultaneously retract said cylinder and piston, compressing said spring and will move said pivoted barrel downward to expose the breech of the shooting barrel.

7. In an air gun, the combination with a 125 shooting barrel, of a hollow frame cut away adjacent to said shooting barrel, an air compression cylinder within said hollow frame normally in alinement with said shooting barrel, and means for depressing said air 130

compression cylinder within said hollow frame to expose the breech of the shooting barrel for loading.

8. In an air gun, the combination with a shooting barrel and a frame rigid therewith, of an air compression cylinder normally in alinement therewith, a piston in said cylin-

der, a spring, and means pivoted upon said frame and connected to said cylinder for compressing said spring and moving said cylinder laterally to expose the breech of said shooting barrel for loading.

In testimony whereof I affix my signature.

CHARLES F. LEFEVER.
